UNITED STATES PATENT OFFICE.

ROBERT J. COLWELL, OF EDGEWOOD, PENNSYLVANIA, ASSIGNOR OF ONE-HALF TO
E. S. SATTERFIELD, OF EDGEWOOD, PENNSYLVANIA.

WEATHER STRIP.

Application filed August 31, 1927. Serial No. 216,631.

This invention relates to a weather strip, and particularly to a metallic construction having a yielding contact with a window or door.

5 In ordinary metallic weather strip construction there is considerable frictional resistance between interlocking parts which renders the window difficult to operate, particularly when climatic conditions cause a 10 swelling or warping of the sash or bead which results in a binding of the sash. This resistance in operation is materially increased when the strip members are tightly connected or tensioned to prevent air leakage between the sash and frame or avoid rattling of the sash under wind pressure.

15 To avoid such objections I provide a freely movable side strip tensioned into contact with the sash and enclosed by a 20 casing having a wall opposite the contact face secured to the window frame to form an abutment for the tensioning spring. This side unit may be mounted upon an end strip secured to the frame and having a 25 yielding contact plate engaging the end of the sash and a stop member against which the casing bears. The parts so far described may be further enclosed by an angle closure plate connected to the casing.

30 This construction forms an air-tight joint at the sides and ends of the sash which economizes fuel by preventing the entrance of air or dirt and prevents rattling of the sash through the tensioning of the strips. 35 This tensioning is so determined as to compensate for warping, swelling or shrinkage of the sash or co-operating beads so that the sash under all conditions is easily slidable as any sticking or binding thereof is eliminated.

40 The strip structure also forms a parting bead between the sashes or may be used as a stop to be engaged by a door when closed.

The invention has for an object to provide a novel and improved construction of a 45 weather strip including a side strip having a lateral closure member and a fixed casing with a cooperating wall between which and the strip a tensioning strip is disposed.

50 A further object of the invention is to present an improved structure in which the side strip is movably mounted upon a fixed end strip having a yielding contact face against the end of a sash.

55 Another object of the invention is to provide an improved construction in which the

strip unit forms a bead or strip having a finished appearance and adapted to bear against the side of the closure with which it cooperates.

60 Other and further objects and advantages of the invention will be hereinafter set forth and the novel features thereof defined by the appended claims.

In the accompanying drawings:

Figure 1 is an elevation showing the invention applied to a window;

Figure 2 is a similar view of the strip applied to a door;

Figure 3 is an enlarged horizontal section of one of the strips applied;

Figure 4 is a detail perspective of the tensioning spring;

Figure 5 is a sectional perspective of the end strip;

Figure 6 is a similar view of the side strips;

Figure 7 is a detail perspective of the casing member;

Figure 8 is a like view of the enclosing shell;

Figure 9 is a plan of the strip shown in Figure 5;

Figure 10 is a similar view of the strip shown in Figure 6;

Figure 11 is a rear elevation of the casing shown in Figure 7;

Figure 12 is a similar view of the outer shell;

Figure 13 is a horizontal section showing a plurality of the strips applied; and

Figure 14 is a similar view of the strip applied to a door.

Like reference numerals designate corresponding parts throughout the several figures of the drawing.

The invention is adapted for various applications in relation to the sashes of a window and the stop members of a door or similar closure. As applied to a window, shown in Figures 1 and 3, the numeral 10 designates the window frame which may be of any desired construction and is provided with a vertically extending channel 11 and also with an inner strip or bead 12 against which the sash member 13 abuts. At the outer face 14 of the sash my improved side strip is applied and this comprises a contact face 15 having an angularly disposed closure flange 16 at one side and an opposite retaining flange 17 extending in the same

100

105

110

direction. Projecting from this retaining flange is an attaching flange 18 extended in a direction opposite to the flange 17 and provided with one or more projections 19 for attachment to an end strip 20 to be hereinafter described.

Cooperating with the side strip 15 is a casing member 21 formed with an angular closure flange 22 having apertures 23 to receive a projecting hooked portion 24 from the flange 16. This hook and slot are so proportioned as to permit relative movement of the parts in order to project the contact surface 15 against the sash. The casing 21 is formed with a rebent portion 25 slotted at intervals as shown at 26 and from which the attaching strip 27 extends substantially parallel with the portion 22 and is secured by fastening devices, as at 28. The flange 22 has a turned free edge 22' to form a reinforcement and tight joint. Intermediate the side strip and casing a tension spring is disposed which may be of any preferred character, a desirable form being of flat metal as indicated at 29 having corrugations 30 so as to provide a plurality of resilient faces extending for the length of the spring which is substantially commensurate with the length of strip used. The unit so far described comprises a side strip which may be used independently of other parts but for the purpose of providing a finished appearance and preventing the entrance of dirt or moisture if exposed to the weather the casing is provided with a closure plate 31 which is attached at its inner end to the slotted portion 25 of the casing by means of projections 32 which are passed through the slots 26 and rebent as shown in Figure 3. The closure plate 31 is formed with the angle portion 33 which overlaps the joint between the side strip and its casing to protect the same and close the side openings therein. This portion has a turned edge 33' acting similarly to the edge 22'.

This construction of side strip may be mounted in cooperation with the end strip 20 and the latter is formed with the angular attaching body 34 secured within the channel 11 of the frame by any desired means such as shown at 35, and the free end of this strip 20 is of resilient character and has an extended bearing surface against the end of the sash as shown at 36 in Figure 3. The free end of this bearing surface 36 is deflected at 37 to provide for its resilient bearing and the opposite end of the portion 36 is slotted at 38 to receive the supporting lugs 19 from the side strip. The end of the angular portion 34 opposite the contact face 36 thereof is rebent as at 44 to form a stop to be engaged by the casing member 21 and provide an abutment.

65 This mounting of the side strip permits

its relative movement upon the end strip while preventing disengagement therefrom and thus compensates for a wide range of adjustment necessary in the shrinkage or warping of the sash or its associated members, as indicated by dotted lines in Figure 3. The strip unit when assembled forms in effect a bead or holding member for the sash and may be used for the continued height of the window at the outer face of the lower sash and also across the top and sides of the upper sash as indicated in Figure 1. A similar strip may also be applied intermediate the upper and lower sash to form the operating bead as shown in Figure 13. 80 If used in connection with a door 40, as shown in Figure 14, the end strip, which is similar to the construction before described, may be disposed in an inclined channel 41 of the door frame 42 so that the side strip 85 forms a stop or abutment for the door as at 43.

In assembling the construction, the end strip may be first mounted within the groove of the window frame and the side strip having its casing and enclosure member previously connected therewith then slid into engagement with the apertures of the end strip and secured by the fastening devices, which assures a firm assemblage of the strips 95 so that their tension may be directly applied against the sash. The construction provides for a side unit which may be associated with a supplemental enclosing shell and mounted upon a cooperating end strip 100 so as to secure pressure against both the side and end of a sash or door as shown in Figures 3 and 14 respectively. This assemblage of parts practically supports the sash by the resilient members of the strips so as to prevent binding or jamming thereof and affords a freely movable window under all conditions. The closure effected prevents both the entrance of air and dirt so as to effect economy in heating and also cleanliness of 105 the apartment having the window to which the strip is applied.

The parts are adapted to be readily formed of sheet material bent into the desired shape and can be applied by unskilled 110 labor so as to secure the most effective results in weatherstripping the window or door.

While the specific details of construction have been shown and described, the invention is not confined thereto as changes and alterations may be made without departing from the spirit thereof as defined by the following claims.

Having thus described my invention, what 125 I claim as new and desire to secure by Letters Patent of the United States is:—

1. A weather strip including a side strip having a lateral closure member, a casing adapted to be secured to a fixed part and 130

having a cooperating closure member, and a tensioning member disposed intermediate the casing and strip.

2. A weather strip including a side strip having a lateral closure member, a fixed casing having a cooperating closure member, a tensioning member disposed intermediate the casing and strip, a fixed end strip having a yielding contact face, and means connecting the side and end strips to permit relative lateral movement.

3. A weather strip including a side strip having a lateral closure member, a fixed casing having a cooperating closure member, a tensioning member disposed intermediate the casing and strip, and an angular finishing plate connected to the casing and overlapping the closure members.

4. A weather strip including a side strip having a lateral closure member, a fixed casing having a cooperating closure member, a tensioning spring disposed intermediate the casing and strip, a fixed end strip having a yielding contact face, means connecting the side and end strips to permit relative lateral movement, and an angular finishing plate connected to the casing and overlapping the closure members.

5. A weather strip including a fixed end strip having apertures and a resilient contact face, a side strip having an angular closure plate and projections entering the apertures of the end strip, a fixed casing formed with an overlapping angular closure plate for the side strip, and a tension spring disposed between the casing and side strip.

6. A weather strip including a fixed end strip having apertures and a resilient contact face, a side strip having an angular closure plate and projections entering the apertures of the end strip, a fixed casing formed with an overlapping angular closure plate for the side strip, and a corrugated flat metal spring extending longitudinally between the casing and the side strip.

7. A weather strip including a fixed end strip having apertures and a resilient contact face, a side strip having an angular closure plate and projections entering the apertures of the end strip, a fixed casing formed with an overlapping angular closure plate for the side strip, a tension spring disposed between the casing and side strip, and an angular finishing plate overlapping the closure plates and having projections entering apertures in the casing.

8. A weather strip including a side strip having a contact face and an angular closure flange, a casing having an attaching flange, and an angular closure flange connected to the closure flange of the side strip to permit relative movement and form a bead member.

9. A weather strip including a side strip

having a contact face and an angular closure flange, a casing having an attaching flange, an angular closure flange connected to the closure flange of the side strip to permit relative movement and form a bead member, a fixed end strip having an angular attaching portion and a slotted resilient contact face, and projections from said side strips slidably mounted in the apertures of said contact face.

10. A weather strip including a side strip having a contact face and an angular closure flange, a casing having an attaching flange, an angular closure flange connected to the closure flange of the side strip to permit relative movement and form a bead member, a fixed end strip having an angular attaching portion and a slotted resilient contact face, projections from said side strips slidably mounted in the apertures of said contact face, a stop face at one edge of the attaching portion of the end strip disposed to engage the casing, and a tensioning spring disposed between the casing and side strip,

11. A weather strip including a side strip having a contact face and an angular closure flange, a casing having an attaching flange, an angular closure flange connected to the closure flange of the side strip to permit relative movement and form a bead member, a fixed end strip having an angular attaching portion and a slotted resilient contact face, projections from said side strips slidably mounted in the apertures of said contact face, a stop face at one edge of the attaching portion of the end strip disposed to engage the casing, a tensioning spring disposed between the casing and side strip, an inwardly projecting flange from the side strip for confining said spring in position, and a finishing shell having an angular face overlapping the closure between the side strip and casing and also projections extending through apertures in the fixed casing member.

12. A weather strip including an end strip having an angular attaching portion adapted to be seated in a groove of a window frame, and a deflected contact face having an extended area against the end of a sash and a cooperating spring tensioned side strip mounted for lateral movement upon the end strip toward and from a side of said sash.

13. In a weather strip, the combination with an end strip fixedly mounted upon a window frame and having a resilient contact face, of a tensioned side strip having a fixed casing and a contact face with a connection laterally movable upon the end strip.

In testimony whereof I affix my signature.

ROBERT J. COLWELL.
